CAR ROOF

Charles David Bonsall, Pittsburgh, Pa., assignor
to P. H. Murphy Company, New Kensington,
Pa., a corporation of Pennsylvania

Application July 25, 1935, Serial No. 33,042

5 Claims. (Cl. 108—5)

This invention relates to car roofs of the type wherein metal roof sheets are secured to metal carlines whose ends rest on the side plates of the car. Such carlines act as beams and heretofore

- 5 it has been the practice to make them by rolling or by pressing homogeneous metal sheets into a cross-sectional shape and area that will enable them to carry their vertical load. It has been the practice to design such carlines so that 10 the neutral axis thereof is midway between the top and bottom thereof and to rivet thereto the overlapping margins of the roof sheets resting thereon. The object of the present invention is to provide a car roof wherein much lighter 15 carlines can be used than have heretofore been used in roofs of the same strength. The invention consists principally in securing the sheets to the carlines by welds of metal of high compressive strength, the cross-section of the carline 20 and of the weld metal being such that the neutral axis of the structure is below the geometrical center lines of the carlines and the unit fiber stress on the weld metal is higher than the unit fiber stress at the bottom of the carlines. It also 25 consists in the carlines and in the combinations of parts hereinafter described and claimed.

In the accompanying drawings, wherein like reference numerals refer to like parts wherever they occur,

- 30 Fig. 1 is a plan view of a part of a car roof embodying my invention, with parts of the roof sheets broken away.

Fig. 2 is a cross-sectional view on the line 2—2 of Fig. 1.

- 35 Fig. 3 is a sectional view longitudinally of the roof but crosswise of the carline on the line 3—3 of Fig. 1.

- 40 Figs. 4 and 4a are sectional views showing an old construction in comparison with the present invention, with numerical data for the comparison, and

- 45 Figs. 5 and 5a, 6 and 6a, 7 and 7a, 8 and 8a, 9 and 9a, and 10 and 10a are comparative views, the vertically alined views at the left illustrating old types of carlines and sheets and the vertically alined views at the right showing the manner of modifying them conformably to my invention.

According to the present invention, the car roof 50 comprises metal carlines 1 whose ends rest upon and are secured to the side plates 2 of the car. Metal roof sheets 3 extend from side plate to side plate with their margins overlapping the carlines but with the margins of adjacent sheets spaced apart. The sheets are secured to the car- 55 lines by welds 4 of alloy steel or other metal of

high compressive strength that fill the spaces between adjacent sheets.

My carline is so designed that the neutral axis thereof is considerably below the geometrical center line of the carline; in fact, it is so far below such geometrical center line that, although the neutral axis of the assembled structure is raised by the metal of the weld and marginal portions of the roof sheets, such neutral axis will still be below the geometrical center line of the carline. By this arrangement, the unit fiber stress on the weld metal is considerably higher than the unit fiber stress on the lower portion of the carline. Accordingly the strength of the structure may be increased even though its weight 15 is decreased, as will appear from the comparison of a specific example of the old construction illustrated in Fig. 4 with the new construction illustrated in Fig. 4a.

Fig. 4 represents an A. R. A. standard carline 20 1a made of a sheet of low carbon steel, of a compressive strength of about 25,000 pounds per square inch, and of a thickness of $\frac{3}{16}$ of an inch, pressed into the form of an inverted channel with an overall depth of 3 inches, an inside width of 25 $1\frac{1}{2}$ inches and with side flanges 5a which are $\frac{3}{4}$ of an inch wide and extend outwardly at the bottom of the carline. Roof sheets $\frac{3}{16}$ of an inch thick overlap each other $\frac{3}{4}$ of an inch and are secured by rivets 6 through such lap to the car- 30 line. In the new construction illustrated in Fig. 4a, the overall depth of the carline 1 and the interior width of the channel are the same as before, namely, 3 inches in depth and $1\frac{1}{2}$ inches in width; but the new carline is pressed from a 35 sheet of low carbon steel only $\frac{1}{8}$ of an inch in thickness and its side flanges 5 are each $1\frac{1}{4}$ inches wide. The roof sheets are of the same thickness as before but, instead of lapping, they are spaced 40 1 inch apart and the space is filled with a weld 4 of alloy steel having a compressive strength of about 90,000 pounds per square inch. From the dimensions stated it follows that the cross sectional area and consequently the weight of the new carline construction, including the weld and 45 one-quarter inch of the adjacent roof sheets, is 24 percent less than the corresponding parts of the old construction.

Further comparing the design of Figs. 4 and 4a, it is noted that although the neutral axis of 50 the old carline alone shown in Fig. 4 is midway between the top and the bottom thereof, that is, 1.5 inches below its upper surface, the neutral axis is raised by the riveting of the sheets to the carline to a point that is only 1.3672 inches below 55

- the top surface of the carline or 1.5547 inches below the upper surface of the top sheet. On the other hand, the neutral axis of the assembly incorporating the carline illustrated in Fig. 4a is 5 1.5271 inches below the top surface. It follows that the section modulus of the old construction of Fig. 4 is 1.2910 and that the section modulus of the new construction of Fig. 4a is 1.0428, which is 19.4 percent less than in the old construction. 10 It follows that, for the same load, the stress in the compression region of the new construction is 19.4 percent higher than in the old construction, but such increased stress is well within the capacity of the weld metal.
- 15 Summarizing the comparison of the old construction of Fig. 4 with the new construction of Fig. 4a, the new construction is 24.4 percent lighter and 24 percent stronger than the old.

While I have described my invention as applied to carlines of inverted channel shape, it is equally applicable to carlines of other shapes. Heretofore, it has been the practice to design such carlines with their upper and lower chords of equal cross-sectional area and consequently with 25 their neutral axes midway between the top and bottom thereof. According to the present invention, the cross-sectional area of the lower chord is considerably larger than that of the upper chord and the neutral axis of the new carline is so far below the geometrical center line 30 thereof that, if the weld metal of high compressive strength is applied to the top thereof, the neutral axis of the assembly will still be low enough to put such weld metal under greater unit 35 stress than would be practicable with metal of less compressive strength. For instance, Fig. 5 represents a riveted construction using a Z-shaped carline A of pressed metal of even thickness and with its upper and lower flanges or 40 chords of even width; in comparison therewith in Fig. 5a is shown my welded construction that uses a lighter Z-shaped carline A' whose lower flange is widened out to increase the cross-sectional area thereof and thereby lower its neutral 45 axis.

In Fig. 6, an old rolled metal carline B of Z-shape section is shown in comparison with a new lighter roller carline B' (Fig. 6a) of Z-shape section whose lower flange or chord is of greater 50 thickness than in the old section.

Fig. 7 compares an old inverted channel shaped carline C with a new inverted channel shaped carline C' (Fig. 7a) of lighter weight but with thick bottom flanges.

55 Fig. 8a illustrates the invention as applied to channel shaped carlines D with lateral top flanges, the new carline D' being of less total weight than the old carline of Fig. 8 and of uniform thickness but the bottom thereof being 60 wider than in the old construction.

Fig. 9 shows an old pressed metal carline E consisting of a vertical web portion and top and bottom flanges of equal width in comparison with the lighter new carline E' (Fig. 9a) of similar shape but with its bottom flange considerably widened.

Fig. 10 illustrates a rolled carline F of channel shape set with its web vertical in comparison

with a lighter rolled carline F' (Fig. 10a) of similar shape except that the lower flange or chord thereof is considerably thickened.

What I claim is:

1. A car roof comprising metal carlines that have an upper chord and a lower chord and a vertical web connecting said chords, roof sheets with their side margins spaced apart and resting on the carlines, and welds of metal of high compression strength uniting adjacent sheets to the underlying carline, the total cross-sectional area of the metal in the lower chord of the carline being substantially greater than the sum of the area of the metal in the upper chord thereof plus the area of the weld, whereby the unit stress on the weld metal is more than the unit stress on the metal in the lower chord. 15

2. A car roof comprising inverted channel shaped carlines with wide lateral flanges of greater sectional area than the tops of the carlines, roof sheets with their side margins spaced apart and resting on the carlines, and welds of metal of high compression strength uniting adjacent sheets together and to the underlying carline, the total cross-sectional area of the metal 25 in the flanges of a carline being substantially greater than the sum of the area of the metal in the top thereof plus the area of the weld, whereby the unit stress on the weld metal is more than the unit stress on the flange metal. 30

3. A car roof comprising pressed metal carlines, roof sheets with their side margins spaced apart and resting on the carlines, and welds of metal of high compression strength uniting adjacent sheets together and to the underlying 35 carline, the total cross-sectional area of the metal in the lower chord of a carline being substantially greater than the sum of the area of the metal in the top thereof plus the area of the weld, whereby the unit stress on the weld metal 40 is more than the unit stress on the metal of the lower chord.

4. A car roof comprising Z-shaped carlines, roof sheets with their side margins spaced apart and resting on the carlines, and welds of metal 45 of high compression strength uniting adjacent sheets together and to the underlying carline, the total cross-sectional area of the metal in the lower chord of a carline being substantially greater than the sum of the area of the metal in the top thereof plus the area of the weld, whereby the unit stress on the weld metal is more than the unit stress on the metal of the lower chord. 50

5. A car roof comprising pressed metal carlines that have an upper chord and a lower 55 chord that is considerably wider than the upper chord and a vertical web connecting said chords, roof sheets with their side margins spaced apart and resting on the carlines, and welds of metal of high compression strength uniting adjacent 60 sheets to the underlying carline, the total cross-sectional area of the metal in the lower chord of the carline being substantially greater than the sum of the area of the metal in the upper chord thereof plus the area of the weld, whereby the 65 unit stress on the weld metal is more than the unit stress on the metal in the lower chord.

CHARLES DAVID BONSALL.
